GALVANIC ANODE ASSEMBLY

Albert F. Craver, Bay Village, Ohio, assignor to The Patrol Valve Company, Cleveland, Ohio, a corporation of Ohio

Application April 3, 1952, Serial No. 280,293

2 Claims. (Cl. 204—197)

This invention relates to means for preventing corrosion, and more particularly, to an improved galvanic anode assembly including means for reducing excessive current flow by means of an electrical resistor and including means for preventing leaking of water from a vessel through the assembly after the anode is consumed.

It is common practice today to use anodes, which are galvanically active to metallic vessels, for minimizing corrosion of such vessels by water contained therein. It is also common practice to place the consumable anode in the water and electrically connect the anode to the vessel. As the anode is consumed an electric current flows in a manner to protect the vessel from corrosion and thereby add appreciable life to the vessel or tank. It has been established that the rate of current flow and the rate of consumption of the anode are relatively proportional to the amount of total dissolved solids in the water. It follows that use of such anodes in waters that have a high content of dissolved solids will cause more current to flow than is required for satisfactory protection of the vessel and will thereby result in rapid consumption of the anode and in formation of excessive quantities of anode corrosion products.

In many instances electrical resistors have been used in reducing and controlling this excessive current flow. Although these resistors are generally enclosed in special adaptor fittings to protect the resistors from contact with the water there is no protection provided to prevent escape of water from the tank or vessel through the adaptor assembly after the anode has been fully consumed.

The current flow between the vessel and the anode assembly containing a resistor is quite small and may be of a value of 10 to 100 milliamperes. Thus, in order to obtain the desired corrosion protection benefits from the anode it is essential that there be permanent electrical connection between all of the current carrying parts and that no resistances be formed in the electrical circuit which will prevent flow of current sufficient for the desired corrosion protection to the tank or vessel.

Therefore, an object of this invention is to provide an improved resistor-anode assembly which will provide permanent electrical contacts between all current carrying parts.

Another object of this invention is to provide an adaptor assembly which will prevent water leaks through the assembly before and after the anode is consumed.

Other objects are to provide an adaptor assembly which is of inexpensive construction, is positive in action, quickly and easily installed, and may be readily adapted to various anode fittings.

These and other objects will be apparent in the course of the following specification.

In the drawings forming a part of this specification:

Fig. 1 is a vertical section through an adaptor assembly;

Fig. 2 is a vertical section of an adaptor assembly including a resistor, mounted on an anode;

Fig. 3 is a vertical section of the adaptor assembly of Fig. 2, mounted in a water tank;

2

Fig. 4 is a vertical section through a modified form of adaptor assembly mounted in a pipe plug; while

Fig. 5 is a vertical section of another modified form of my invention showing the adaptor assembly secured to a combination anode support and water-outlet fitting fixture which is mounted in a water tank.

An illustrative embodiment of my invention disclosed in the accompanying drawings in Figs. 1, 2 and 3 comprises an adaptor assembly or anode support 10, preferably formed of brass or some other suitable material, having a bore 11, and a counter bore 12, at the base thereof. The adaptor support body 10 is provided with external threads 13 at one end, while the opposite end is provided with a wall 14 adapted to be rolled inwardly at one end forming an inwardly projecting flange 15. A washer 16 and bushing 17, formed of some suitable dielectric material which will not absorb nor react with water to any appreciable extent, are mounted in the counter bore 12. The bushing 17 is pressed into the counter bore 12, and then the end of wall 14 is turned or formed over forming the flange 15, serving to lock firmly the bushing 17 in fixed position in the counter bore 12 of the adaptor 10. A metal plug 18 having a drilled hole 19 therein is pressed into the end of bore 11.

The adaptor member 10 is constructed and arranged to be mounted over the end of a sacrificial anode 20 formed of magnesium or some other suitable material, having a reduced end portion 21, provided with grooves 22, which due to the flexibility of the bushing 17 will firmly lock the reduced end 21 of the anode 20 thereto. The anode 20 has a shoulder 20a formed at the top and is provided centrally with a core wire 23 projecting through the upper end of the anode 20, where it is soldered at 24 to a terminal 25 of a cartridge resistor 26 having its upper terminal 27 extending through drilled hole 19 and soldered to metal plug 18 at 28. It has been found to be desirable to extend the soldering over the margins of the metal plug 18 to provide additional protection against water leaking into the interior of the adaptor 10 and to provide secure mechanical support for the resistor 26, as shown in the drawings.

It has been discovered that for satisfactory anodic protection of water tanks having relatively highly mineralized waters, a resistor having a resistance on the order of 20 to 30 ohms may be used. Obviously the required resistance will vary according to various factors present, as will be readily understood.

The adaptor support assembly 10 having resistor 26 mounted therein, as illustrated in Fig. 3 may be mounted in a hot water tank 30 having a plug 29 engaging the cooperating threads thereof. For certain installations it may be advantageous to use the form of adaptor 10a illustrated in Fig. 4, where the assembly is an integral part of pipe plug 36.

It may be noted here that the anode support comprises what has been referred to as the adaptor support assembly or support body 10, which has the threaded engagement connecting it with the wall of the tank and includes the insulating supporting means embracing the end of the anode 20. Thus, these elements may be termed an adaptor supporting means or element.

In assembling the device it has been found expedient to solder the upper end of core wire 23 to the terminal 25 of resistor 26 at point indicated at 24. The anode 20 and resistor 26 are then inserted into bushing 17 into which the anode is so fitted as to provide a water-tight joint. Due to the fact that the bushing 17 and the magnesium anode 20 are both slightly resilient, some of the bushing material will be forced into the anode grooves 22 and the sharp edge of the grooves 22 will be forced into the bushing 17, providing firm union of these parts to protect them during transportation. The metal plug 18 having the small drilled hole 19, of a diameter slightly

larger than the terminal 27 is thereaded thereover and pressed into the upper end of the bore 11 of the adaptor 10. The upper end of the terminal 27 is then soldered to the adaptor 10 and plug 18, and the entire assembly may then be connected to a suitable water tank fitting, the external adaptor threads 13 providing permanent electrical contact therewith.

The soldered connections at 24 and 28 assure permanent electrical contact during the life of the anode. When the anode 20 has been consumed due to the corrosion process, water under pressure will enter cavities 12 and 11. This water cannot however leak through the fitting 10 and 10a, due to the permanent soldered joint at 28 with plug 18 of fitting 10 and 10a. Where the assembly is used as in Fig. 4, a water permanent joint is of major importance since parts of the fitting 10a would be outside the water vessel.

The embodiment of the invention described in Fig. 5 illustrates the use of my invention on a combination outlet fitting and anode constructed in accordance with the teachings of United States Letters Patent No. 2,486,936 issued November 1, 1949, which includes an outlet fitting 31 having a thread 32 adapted to be secured in a threaded aperture in a water tank and a socket 33, adapted to receive the outlet pipe of a water distribution system. The fitting 31 has a lateral opening 35 below the thread 32 permitting the flow of water from the tank through the fitting 31. The lower end of the fitting 31 is provided with an inwardly threaded socket 34 receiving the adaptor 10b which corresponds to adaptor 10. The resistor 26 and associated parts shown in the adaptor 10b are similar to the corresponding parts shown in Figs. 1 through 4 and function in a similar manner, as will be readily understood.

It will be apparent to those skilled in the art, that the invention disclosed herein may be variously changed, used or modified without sacrificing the advantages thereof or departing from the spirit thereof, and that the embodiment of my invention disclosed herewith is illustrative only and that my invention is not limited thereto.

I claim:

1. A galvanic anode assembly supporting means adapted to be inserted through the wall of a metal hot water tank of the type including a metal anode projected into the tank, said anode having a ferrous metal core wire 45 extending longitudinally within and along the same, a metal water outlet fitting for supporting the anode and core and electrically connecting it with the tank, the fitting having an axial water passage therethrough, connecting means at the outer end of the fitting for connect-

ing it with piping, external threads around the fitting inwardly of the connecting means for supporting the fitting on the tank and electrically connecting the fitting and the tank, the fitting having a lateral opening inwardly of the external threads, leading from the axial passage through the surface of the fitting, the improvement comprising a metal anode supporting element secured to the inner end of said water outlet fitting and provided with a recess into which the upper end of said anode extends, electric insulation interposed between the supporting element and said anode, a resistor of the cartridge type having longitudinally oppositely extending terminal wires disposed in said recess one of said wires being bonded and electrically connected directly to the adjacent end of said core wire, and the other projecting longitudinally from the cartridge through said anode supporting element and having its end portion electrically bonded to the supporting element, whereby said terminal wires hold the resistor spaced from the inner wall of said recess.

2. An anti-corrosion device for protecting the interior walls of a ferrous metal hot water tank, comprising a metal adaptor supporting element threaded exteriorly for securing it in a threaded opening in the tank wall and having a central bore forming a recess and an end wall element having a relatively small opening therethrough, an elongated metal anode including an electrically conductive and supporting wire core extending therethrough and projecting beyond the surface at one end of the anode, supporting and insulating means interposed between the said adaptor supporting element for retaining said end of the anode in a portion of the bore of the adaptor supporting element, and a cartridge type resistor disposed in said recess having self-supporting terminal wires projecting from its opposite ends, one of said terminal wires being firmly bonded to the projecting end of said core wire and the other of said terminal wires projecting through the small opening in said end wall and being secured therein by electrically conductive bonding material also closing the opening through which the terminal wire projects, and whereby the cartridge is supported by its terminals in spaced relation from the surface of the bore.
